UNITED STATES PATENT OFFICE.

AUGUSTUS KELLOGG SLOAN, OF BROOKLYN, NEW YORK.

DESIGN FOR A BINDING-POST.

45,358.

Specification for Design.

Patented Mar. 3, 1914.

Application filed November 4, 1912. Serial No. 729,501. Term of patent 14 years.

To all whom it may concern:

Be it known that I, AUGUSTUS KELLOGG SLOAN, a citizen of the United States, residing at Brooklyn, in the county of Kings and State of New York, have invented a new and original Design on Binding-Posts, of which the following is a specification, reference being had to the accompanying drawing, forming a part thereof, which is a view in side elevation of a binding-post, showing my new design.

I claim—

The ornamental design for a binding post as shown.

A. KELLOGG SLOAN.

Witnesses:

REID G. FORD,
GEORGE L. MOORE.
